HARNESS CAM CONTROL

Edward Messer, Kannapolis, N. C., assignor to
 Cannon Mills Company, Kannapolis, N. C., a
 corporation of North Carolina

Application September 1, 1938, Serial No. 228,064

4 Claims. (Cl. 139—79)

This invention relates to a new and improved harness cam control for looms and is designed particularly for looms for weaving terry cloth.

An object of the invention is to provide means for a plain or cam loom for reversing the shedding so as to reverse the terry in order that the warp thread or pattern appearing upon one side of the cloth may be continued upon the opposite side so as to produce a cloth having the pattern upon opposite sides reversed and with the terry weave continued perfectly.

A further object of the invention is to provide clutch control means under the control of high balls on a pattern chain or the like for controlling the cams provided, which in turn control the treadles for the harness for the terry warp, whereby warp of contrasting colors may be reversed from the top to the bottom or vice versa.

A still further object of the invention is to utilize the clutch means mentioned above for controlling the weave of ordinary towels with the usual three pick terry which is the incorporation into the body of the towel of a row of loops or piles at every third pick of the loom.

A further object of the invention is to provide simplified means for changing the sequence of operation of the cams upon the treadles so as to reverse the colors in the warp.

A still further object of the invention is to provide means for controlling the stopping stations of the cams so as to insure proper operation of the clutch means.

A further object of the invention is to associate the clutch release cam with the driving gear for the ground warp.

With the above objects in view and others which will appear hereinafter, the invention includes the arrangement and combination of parts hereinafter more fully described, and shown in the accompanying drawings in which:

Figure 1 is a side elevation, partly broken away and with portions of a plain loom omitted for greater clarity illustrating the invention;

Figure 2 is a front elevational view with portions of the loom broken away and omitted;

Figure 3 is a fragmentary plan view illustrating particularly the cam and clutch construction for controlling the operation of the harnesses;

Figure 4 is a cross-sectional view with parts in elevation of the cam and clutch controlling means;

Figure 5 is a cross-sectional view taken on the section line 5—5 of Figure 4 looking in the direction of the arrows, and

Figure 6 is a diagrammatical view on an en-

larged scale of a portion of the cloth illustrating the reversal of the terry.

In the weaving of terry cloth, the particular pattern begun must generally be continued throughout the length of the cloth, unless a Jacquard mechanism or a high price dobby loom is used. With the present invention, it is possible to weave upon a plain or cam loom terry cloth having various designs and to change from one to another and continue weaving in perfect order without breaking the pattern and without producing an imperfect place in the cloth. Thus, a stripe or block of any color may be the beginning of the pattern upon one side of the cloth while upon the reverse side directly opposite such stripe or block the latter will not be affected. A change may be made in the design at any point so that the stripe on one side may terminate and be transferred to the opposite side of the cloth while the differently colored stripe upon the opposite side will be transferred so as to form a continuation of the other colored stripe or block.

In the drawings in which similar reference characters indicate like parts, the ground warp beam is shown at 5 and the pile warp beam at 6. The whip roll for the ground warp is illustrated at 7 and the let-off roll for the pile warp at 8. A companion roll 9 cooperates with the let-off roll 8. The ground warp G from the beam 5 passing over the whip roll 7 is divided between the rear harness frames 10 and 11, while the pile warp T is divided between the front harness frames 12 and 13.

The rear harness frames 10 and 11 are connected together by straps 14 which extend over rollers 15 mounted on an oscillatable shaft 16 supported by the fixed bearings 17 on the loom frame.

The front harness frames 12 and 13 are connected together by straps 18 which extend over rollers similar to the rollers 15 which are secured to the oscillatable shaft 19 which is mounted in the fixed bearings 20 provided on the loom frame.

The pile warp T is preferably of contrasting colors and the invention is particularly directed to the means for controlling the dividing of the pile warp by the harness frames 12 and 13. The terry forming mechanism has been omitted but may be of any desired type.

The loom is provided with the usual shaft 21 and on this shaft is fixed a pinion 22 which meshes with the pinion 23 fixed to the auxiliary shaft 24 mounted in suitable bearings.

The shaft 21 is also provided with a pinion 55

25 which meshes with a gear 26 rotatably mounted on the shaft 24. The gear 26 is fixed to a tubular shaft 27 which rotates on the shaft 24. Also mounted on the tubular shaft 27 and fixed thereto is a collar 28 having an enlarged portion 29 provided with diametrically opposed slots 30 in which are located the lugs 31 on a sleeve 32 axially slidable upon the collar 28.

The sleeve 32 is provided with a circular groove 33 in which engages the forked end 34 of the lever 35 pivotally mounted upon the pin 36 attached to the loom frame work. The movements of the lever 35 are controlled by the pattern chain and a cam which will be described below.

15 Rotatably mounted upon the tubular shaft 27 between the gear 26 and the collar 28 are the cams 37 and 38. The cams 37 and 38 are integral with the hub portion 39 or may be fixed thereto. The hub portion 39 on the side facing 20 the sliding sleeve 32 is provided with a collar portion 40 in which are provided spaced apertures 41 also designed to cooperate with the lugs 31 of the sliding sleeve or clutch element 32. The collar 40 is preferably provided with six 25 equally distanced spaced apertures 41. Referring to Figure 3 it will be noted that the lugs 31 always extend to some extent into the slots 30 upon the enlarged portion 29 of the collar 28, but when the lever 35 is swung in the direction of the arrow in this figure, the lugs 31 will 30 extend through the slots 30 and into the slots 41, thereby coupling the hub portion 39 with the cams 37 and 38 to the sleeve 32 which in turn is 35 coupled with the collar 28. When such action 35 takes place, the gear 26, the hub portion 39 and the collar 28 will rotate as a unit with the tubular shaft 27 on the shaft 24.

In order to ensure the proper alignment between the slots 41 and the slots 30 at the clutching stations, the hub 39 is provided on the side 40 opposite the collar 40 with a collar 42 in which are provided arc shaped depressions 43 with which a roller 44 cooperates. The roller 44 is 45 rotatably mounted on the pin 45 secured to the lever 46. One end of the lever 46 is screw threaded as shown at 48 and threads into the socket member 49, which in turn is pivotally mounted on the stud shaft 47 between the collars 50 50 fixed to the stud shaft. The stud shaft 47 is mounted in an extension 51 of the loom frame. The threading of the lever 46 in the socket member 49 permits an exact positioning of the brake roller 44 so as to ensure a proper alignment of the slots 43, 41 and 30.

55 The other end of the lever 46 is provided with a notched portion 52 in which engages the wire 53 which in turn is connected to a spring 54 which is secured at its other end to the loom frame at any desired position. The spring 54 urges the roller 44 against the collar 42 at all 60 times.

As above mentioned, the gear 23 is fast to the shaft 24. Also secured to the shaft 24 are the cams 55 and 56 which are integrally connected 65 together. These cams control the shedding of the ground warp, while the cams 37 and 38 control the shedding of the pile warp. The treadle levers 57, 58, 59 and 60 cooperate with the cams 55, 56, 37 and 38 respectively. The treadle levers 70 are pivotally mounted at one end upon the shaft 61 and each is provided with a cam roller 62 held in contact with the respective cam. The free ends of the treadle levers are connected by the straps 63 to the harness frames 10, 11, 12 75 and 13.

The controls for the lever 35 which in turn controls the operation of the cams 37 and 38 will now be described. Fixed upon the shaft 24 is a cam disc 64 having a cam track 65. A cam roller 66 cooperating with the cam track 65 is 5 pivotally connected to one end of the lever 67 which is fixed in turn to the shaft 68 rotatably mounted in the loom frame extensions 69. Also fixed to the shaft 68 is a lever 70 which has a slot 71 in which is adjustably fixed a pin 72 as 10 by means of the collars 73. A connecting rod 74 is loosely connected at one end, as particularly shown in Figure 3, to the lever 35 and the other end of the connecting rod 74 is of hook shape as shown at 75 in Figure 2 and engages 15 over the pin 72. The connecting rod 74 is guided by the guide member 76 fixed in any desired way to the loom frame. In order to permit adjustment of the lever 35 such lever is threaded into a socket member 77 which in turn is pivoted on the pin 36. The nuts 78 and 79 threaded upon the lever 35 encloses the end of the connecting rod 74 which is connected to the lever 35. In the construction shown, the connecting rod 74 is provided with an eye 80 which can be 20 slipped into position over the lever 35 when the lever 35 is disconnected from the socket member 77.

25 The spring 81 is connected at one end to the loom frame and the other end is connected to 30 a wire 82, which in turn is secured to the lever 70 and by this means the cam roller 66 is held in contact with the cam track 65 at all times. Also secured to the loom frame is a spring 83 which is secured to a wire 84 secured in turn to 35 the socket 77 and the spring 83 tends to hold the lugs 31 engaged in the apertures 41 until released therefrom by the action of the cam roller upon the raised portion of the cam track. The springs 81 and 83 supplement one another in their 40 action.

45 The other control for the lever 35 and consequently the clutch mechanism is from the pattern chain and is shown particularly in Figures 1 and 2. The chain rack is shown at 85 and pivoted thereto is the high ball lever 86. The free end of the high ball lever 86 is pivotally connected to the rod 87 at one end and the other end of the rod 87 is pivotally connected to one arm of the bell crank lever 88 which is pivotally connected 50 to the loom frame at 89. The other arm of the bell crank lever 88 is pivotally connected at one end of the rod 90 whose other end is pivoted at 91 in an eye provided at the end of the lever 74. A high ball going into contact with high ball 55 lever 86 will raise the same, pivot bell crank lever 88 and lift the end of the lever 74 thereby disengaging the hook portion 75 from the pin 72.

60 The gear 26 is preferably provided with sixty-three teeth and the driving pinion 25 on the shaft 21 is provided with twenty-one teeth. The shaft 21 may be driven from any desired moving part of the loom. The cam 55 is a double pick cam and the cam 56 is a single pick cam. The cams 37 and 38 have a configuration as shown particularly in Figure 5. One complete revolution of the cams 37 and 38 is equal to 9 picks in the cloth. The raised portion of the cam track 65 will disengage the clutch after the shed is formed for the third pick, thereby bringing the cams 37 and 70 38 to a complete stop. The clutch will again engage after the first pick. The third and the first pick are exactly alike making one complete repeat. A point on cam 38 being directed downwardly will depress treadle lever 60 and bring 75

harness frame 13 downwardly and the harness frame 12 controlled by treadle lever 59 is brought upwardly for the first pick, after which the clutch becomes engaged. A point on cam 37 being brought downwardly depresses treadle lever 59 and brings harness frame 12 downwardly and harness frame 13 upwardly for the second pick. Then a point on cam 38 again depresses treadle lever 60 with a movement downwardly of harness frame 13 and a movement upwardly of harness frame 12 for the third pick which is exactly like the first pick with the one difference being in the beat up which is after the third pick. This is the operation when the cams 37 and 38 are subjected to the control from the cam disc 64, the clutch being disengaged during the first and third picks.

When the colors are reversed in the pile warp, the cams 37 and 38 operate exactly opposite. In this case whenever a high ball on the pattern chain lifts the high ball lever 86, the rod 90 will disconnect the hook shaped end 75 from the pin 72 thereby preventing a disconnection of the clutch by the raised portion on the cam track 65. This will permit the cams 37 and 38 to remain in operation for three consecutive picks, which in turn will change the motion of the pile warp harness frames 12 and 13 to the opposite from that which they were weaving. For instance, if the harness frame 13 was weaving two picks up and one pick down this will be changed to the harness frame 12 weaving two picks up and one pick down. Since the cams are three point cams and are positioned oppositely on the tubular shaft 27, any operation due to the high ball on the pattern chain will permit the clutch to remain engaged for three picks in succession. This will reverse the order of the cam points and in turn reverse the order of action of the harness frames. With regard to the ground warp cams 55 and 56, these make one complete revolution every three picks or one repeat. Without the clutch releasing cams 64, 65, and 66 one would get merely a two harness weave effect in the cloth, but with the cam construction mentioned in contact all the time, it is possible to get the plain terry weave effect in the cloth.

Figure 6 illustrates the reversal of the terry which is secured when a high ball operates the lever 74 and allows the clutch to remain engaged for three consecutive picks.

I claim:

1. A harness control for looms for weaving terry cloth comprising a gear rotated by a moving part of the loom, a double pick cam and a single pick cam continuously rotated by said gear controlling the harness frames for the ground warp, a cam disc also continuously rotated by said gear,

a second gear also rotated by a moving part of the loom, freely mounted cams for controlling the operation of the harness frames for the pile warp, means for coupling said freely mounted cams with said second gear, means operated by said cam disc controlling said coupling means and means for rendering said means controlling said coupling means inoperative in order to reverse the operation of the harness frames for the pile warp.

2. A harness control for looms for weaving terry cloth comprising a gear rotated by a moving part of the loom, a double pick cam and a single pick cam continuously rotated by said gear controlling the harness frames for the ground warp, a cam disc also continuously rotated by said gear, a second gear also rotated by a moving part of the loom, freely mounted cams for controlling the operation of the harness frames for the pile warp, means for coupling said freely mounted cams with said second gear, means operated by said cam disc controlling said coupling means and means operated by a pattern chain, for rendering said means controlling said coupling means inoperative in order to reverse the operation of the harness frames for the pile warp.

3. A harness control for looms for weaving terry cloth comprising a shaft, a gear rotated by a moving part of the loom continuously rotating said shaft, a double pick cam and a single pick cam fixed to said shaft controlling the harness frames for the ground warp, a cam disc fixed to said shaft, a tubular shaft rotatably mounted upon said shaft, a gear fixed to said tubular shaft and rotated by a moving part of the loom, cams rotatably mounted on said tubular shaft controlling the harness frames for the pile warp, means for coupling said last named cams to said tubular shaft and means operated by said cam disc controlling said coupling means.

4. A harness control for looms for weaving terry cloth comprising a shaft, a gear rotated by a moving part of the loom continuously rotating said shaft, a double pick cam and a single pick cam fixed to said shaft controlling the harness frames for the ground warp, a cam disc fixed to said shaft, a tubular shaft rotatably mounted upon said shaft, a gear fixed to said tubular shaft and rotated by a moving part of the loom, cams rotatably mounted on said tubular shaft controlling the harness frames for the pile warp, means for coupling said last named cams to said tubular shaft, means operated by said cam disc controlling said coupling means, and means for rendering said means operated by said cam disc inoperative at predetermined intervals.

EDWARD MESSER.
